UNITED STATES PATENT OFFICE.

ALFRED G. SEYDEWITZ, OF MUSKEGON, MICHIGAN.

KNOCKDOWN FURNITURE.

No. 919,257.

Specification of Letters Patent.

Patented April 20, 1909.

Application filed March 2, 1908. Serial No. 418,854.

To all whom it may concern:

Be it known that I, ALFRED G. SEYDEWITZ, a citizen of the United States, and resident of the city of Muskegon, county of Muskegon, 5 State of Michigan, have invented certain new and useful Improvements in Knockdown Furniture, of which the following is a specification, and which are illustrated in the accompanying drawings, forming a part 10 thereof.

The invention relates to furniture adapted to be folded to compact form for storage or transportation and has for its object to provide an improved article of furniture which 15 may be readily folded or extended, which shall occupy a minimum of space when folded and which shall be both light in weight and of great strength when extended.

The invention contemplates improved 20 means for connecting the parts of furniture for folding which may be readily embodied in the construction of furniture of various forms and which will admit of such furniture being made to conform to any desired artistic 25 pattern or style.

In the accompanying drawings: Figure 1 is a side elevation of a table embodying the 30 features of the invention, the parts being shown in the extended position of service. Fig. 2 is a plan view of the same, partly in 35 horizontal section, the plane of the section being indicated by line 2—2 on Fig. 1; Fig. 3 shows in perspective the supporting legs of the table illustrated in Figs. 1 and 2 in folded 40 position; and Figs. 4 and 5 show in perspective the shelves of the table illustrated in Figs. 1 and 2 separated from other parts.

A small table or stand of the form commonly termed a taboret is illustrated in the 45 drawings for the purpose of disclosing the invention. As shown, this taboret comprises a plurality of supporting legs as 10, 11, 12, 13, 14 and 15 hinged together as at 16, 17 to fold about the vertical axis of the table. Preferably two sets of hinges, 16, 17, are provided, and as shown these are applied respectively to the inner ends of horizontal arms 18, 19, so formed upon each of the standards or legs, 10, 11, 12, 13, 14, 15 that 50 the arms are radially disposed about the vertical axis of the table when the parts are in the extended position of service illustrated in Figs. 1 and 2. The hinges 16, 17 may be conveniently formed of flexible fabric firmly 55 secured to the inner ends of the arms 18, 19,

as by means of tacks or screws, 20, 21, most clearly shown in Fig. 3.

The arms 18, 19 of the standards designated 10 to 15 inclusive, may each serve to removably support a platen or shelf of the 60 table, that carried by the arms 18 when the table is extended for use being designated by the numeral 22 and being shown in detail in Fig. 4 of the drawings and that carried by the arms 19 being designated by the numeral 23 65 and being shown in detail in Fig. 5.

Means are preferably provided for securing the shelf 22 in place upon its seat on the arms 18 when the standards are extended. A recess 24, shown as being formed in each of the 70 standards 10, 11, 12, 13, 14, 15 at the base of the arm 18 for receiving the periphery of the shelf most conveniently serves this purpose. As shown the table shelf 22 is circular in form and in setting up the table for use the marginal edge of this shelf will be applied to each of the recesses 24 when the standards or legs of the table are in the folded or partially folded position. These standards will then be extended by the flexing of the hinges 16, 75 17 to encircle the shelf as indicated in Figs. 1 and 2 and the shelf is thus firmly secured in place by an inter-engagement between its periphery as at 25, 26, 27 Fig. 2 and the recesses 24 of the standards. 80 85

It is desirable that detachable means be provided for maintaining the standards 10, 11, 12, 13, 14, 15 in the extended position illustrated in Figs. 1 and 2. As shown the platen or shelf 23 carried by the arms 19 of 90 the standards is employed for this purpose. To this end this shelf is preferably provided with a plurality of peripheral notches 28, one for receiving an appurtenance of each of the standards, as the lug 29 which rises from each 95 of the arms 19 adjacent its outer end.

In use the platen or shelf 23 will be applied to its seat upon the instanding arms 19 of the supporting standards after these standards have been rotated upon the hinges 16, 17 100 about the platen or shelf 22 to the extended position illustrated in Figs. 1 and 2. The engagement between the lugs 29 and the notches 28 thus effected serves to securely lock the standards in the extended position. 105 When it is desired to fold the table for storage or transportation the platen 23 will be first removed by lifting it from its seat. The standards 10, 11, 12, 13, 14, 15 may then be turned upon the hinges 16, 17, to the folded 110

position illustrated in Fig. 3, thus releasing the upper platen or shelf 22.

When the parts of the table are in the extended position of use illustrated in Figs. 1 5 and 2, the hinges 16, 17, are quite concealed from view and the external appearance of the device gives no indication whatever of its collapsible character. When, however, the parts are in the folded position the device occupies but little space and is of that compact 10 form wherein there are no projecting parts likely to be broken by rough handling. Articles of furniture such as that described and embodying the features of the invention are 15 exceedingly convenient for use where large numbers of a particular form of article are to be temporarily employed. A great number of such articles may be conveniently carried to the place of use in the folded form and 20 may then be readily set up for use, the upper platen 22 being applied to the recesses 24 of the standards as these are spread out to the extended position and the standards being then locked in place by a fitting of the lower 25 platen upon the arms 19 whereby one of the lugs 29 is caused to enter each of the notches 28. When such a temporary use of these devices has been completed they may be again folded and returned in compact form for storage. 30

I claim as my invention:—

1. In a collapsible article of furniture, in combination a set of standards hinged together to fold about the vertical axis of the article, each of the standards being horizontally notched and the mouth of each of the 35

notches being directed inwardly when the set of standards is unfolded, and a shelf having a continuous circular periphery engageable with the notches of the standards. 40

2. In a collapsible article of furniture, in combination, a set of standards hinged together to fold about the vertical axis of the article, each of the standards being horizontally notched, and a removable shelf carried by the standards the margins of the shelf being interlocked with the notches of the standards to prevent vertical displacement of the shelf when the set of standards is unfolded. 45

3. In a collapsible article of furniture, in combination, a plurality of standards, each having a pair of horizontal shelf supporting arms arranged at different levels and each of the standards being horizontally notched at 50 the base of one of the arms, the mouth of the notch being in the direction of the length of the arm, an upstanding lug formed on the other arm of each of the standards, hinges uniting the arms of the two sets at their ends, 55 a shelf carried by the set of arms adjacent the notches formed in the standards having a plurality of marginal bearing points each engageable with the notch of one of the standards, and a shelf carried by the other set of 60 arms, the last-named shelf being notched to receive the upstanding lugs of the second set of shelf supporting arms. 65
